VARIABLE CAPACITY RECIPROCATING PUMP

William T. Stephens, Cleveland, Ohio, assignor,
by mesne assignments, to Hydraulic Equipment
Company, Cleveland, Ohio, a corporation of
Ohio

Application February 1, 1945, Serial No. 575,699

18-Claims. (Cl. 103—37)

1

This invention relates to reciprocating or plunger pumps and particularly to pumps of that type for delivering liquids under relatively high pressure and adapted to automatically change from high to low capacity whereby higher pressures may be obtained without materially greater effort.

The pump of the present invention is particularly intended for manual operation in the manipulation of tools such as hydraulic vises, arbor presses and the like and it is the purpose of the present invention to materially simplify the construction and operation of these devices.

It is, therefore, an object of the invention to provide a pump assembly including a reservoir, a submerged pump and a release valve together with means for automatically shifting the pump from large to small capacity.

More particularly, it is one object of the invention to provide a pump having a piston rod of substantial area operating in the inlet side of the pump cylinder together with a return valve between the discharge and inlet sides of the pump cylinder subject to operation by increase in discharge pressure for the pump.

A further object of the invention is to provide in a pump of the large connecting rod type of an auxiliary liquid inlet on the discharge side of the piston which auxiliary valve functions only on high capacity operation of the pump.

As a further important feature of the invention there is contemplated the arrangement of a dual transfer valve and return valve housed within the piston.

Other and further objects and features of the invention deal particularly with simplification of construction, the reduction of machine work and the lowering of cost of pump assemblies.

It will be clear as the description proceeds that additional objects and features of the invention are incorporated in the disclosure which illustrates but a single exemplary embodiment of the invention, it being understood that such changes and modifications may be made therein as fall within the scope of the appended claims without departing from the spirit of the invention.

In said drawings:

Fig. 1 is an end elevation looking from the left in Figure 2 of a pump assembly constructed in accordance with the present invention;

Fig. 2 is a longitudinal vertical central section through a pump assembly constructed as described herein, and

Fig. 3 is a fragmentary section similar to Fig. 2 but on an enlarged scale for illustrating the actual pump and valve mechanism.

2

The apparatus of the present invention includes a manually operable pump intended for supplying relatively small quantities of liquid at high pressure for the operation of such devices as arbor presses, hydraulic vises and various other tools of a similar nature. The apparatus is self-contained and can be used without additional valves or accessories for operating any small capacity, single acting hoist or ram of the spring or load returned variety when coupled to the ram cylinder by means of a single pipe or conduit.

The assembly includes a reservoir for a suitable quantity of liquid, a pump mechanism and its valves, a relief valve to prevent excess pressure from damaging any of the equipment and a release valve whereby the liquid may be discharged from the tool ram so that the latter can return to its initial position under the action of its spring or load. For convenience the assembly is arranged for mounting on the floor or base of a machine and the pump is operated by a foot pedal, the downward movement of which provides the delivery stroke. The pedal is returned to position for further operation by a spring conveniently incorporated in the pump cylinder. The liquid used with the pump is preferably a lubricating oil or like material which lubricates and protects the working parts.

Referring to the drawings and first to Figs. 1 and 2, it will be seen that the assembly is incorporated in a single casting or housing 10 having near the top a reservoir compartment 11 supported by laterally spaced legs 12 and spaced integral feet 13 each of which is perforated at several positions, as shown, to receive suitable hold-down bolts.

The reservoir 11 is of suitable capacity to hold the quantity of oil desired for the operation of whatever tool is to be connected to the pump assembly. It is completely closed except for a filler opening covered by cap 15 of the screw type having a vent aperture 16 for the entrance and egress of air during the operation. A dust cap 17 with a pendulous skirt protects the vent. For convenience in manufacture the casting is provided with a re-entrant part above and between the spaced legs and adapted to be submerged in the oil in the reservoir. The whole casting is here provided with a vertical bore 20, the upper portion of which is threaded to accommodate the filler cap and the spaced lower portion of which constitutes the pump cylinder or barrel.

The top of the cylinder is closed off from the upper portion of the reservoir by means of a cylinder head 21 of inverted cup shape having a close fit in the cylinder walls and adapted to be

secured therein by a set screw (not shown) whose inner end is received in the circumferential groove 22. The opposite end of the cylinder bore is closed by a head 24 likewise having a close fit within the bore and adapted to be held in position by tapered drive pins 25. Each of the cylinder heads is provided with a circumferential packing 26 of the expandable type to prevent leakage. The piston which works between the two heads is shown generally at 28 and is mounted by means of threads 29 on the upper end of a piston rod 30 of substantial diameter provided with circumferential grooves 31 to receive flexible packings adapted to provide a tight working fit in the bore 32 in the lower cylinder head 24.

The spaced legs 12 provide convenient mounting means for the pivot pin 34 for the lever carrying the operating pedal 35. As seen in Fig. 1 this pivot 34 is a substantial pin fitting in transverse openings in the legs where it is secured by means of cotters. The cast pedal assembly includes a drilled boss 37 journalled on this pin 34. The opposite end of the pedal lever is bifurcated as at 38 and mounted between the furcations is the roller 39 journalled on pin 40 extending through these members. This roller is directly beneath and contacts the flat bottom surface of the piston rod so that pressure downwardly on the pedal lifts the rod and with it the piston 28. The pedal is returned to the operating position shown in Fig. 2 by means of the heavy helical spring 42 mounted between the upper end of the piston and the underside of the cylinder head 21.

The cylinder bore 20, aside from coming out through the bottom of the casting and entering into the main portion of the reservoir 11, intersects a lateral chamber 44 just below the upper head and a lateral inlet chamber 45 extending just above the lower head. Where it extends to the left, the upper lateral chamber 44 intersects a vertical bore 46 which is counterbored above and intersects the extension 47 of the reservoir. A relief valve 48 is mounted to close the bore 46 and is positioned by means of a spring 49 adjustably tensioned by means of a threaded rod 50 mounted in the screw cap 51 closing aperture 52 in the top wall of the reservoir. Suitable lock and sealing means close off the end of the adjustable rod 50 in a conventional manner. It will be seen that the relief valve 48, which is non-circular in cross-section and has a conical end to engage with the seat at the junction of the large and small bore 46 will be lifted when excess pressure occurs in 44, or above the piston, and will release the liquid causing this pressure into the reservoir.

The inlet chamber 45 connects to the space beneath the piston 28 at all times by virtue of the piston being slightly elevated on spaced annular segments 53 projecting up from the lower cylinder head 24 as best seen in Fig. 3. This chamber 45 is adapted to be connected to the lower chamber 55 of the reservoir by means of a straight vertical bore 56 which houses the inlet valve plunger 57. This plunger is generally of the type which includes a longitudinally bored cylindrical stem 58 which has a close working fit in the bore 56 and a conical head 59 which seats at the junction of the bore 56 and the top wall of the compartment 45. Lateral openings 60 connect with the central bore so that when the valve is opened to the extent that these openings clear the bore fluid can flow freely through the central bore of the stem and out through the lateral openings

60 and beneath the raised head affording passage from 55 to 45. This opening is automatically effected when the pressure is reduced in 45 by the lifting of the piston 28. The valve 57 which 5 will hereinafter be termed the inlet valve for the pump is held closed by means of a suitable spring 61 engaging over a pin 62 on the head of the valve and supported at the opposite end by pin 63 integral with the inner end of a screw plug 64.

10 The discharge valve for the pump is shown at 66 and is of identical construction and size to the inlet valve and is mounted in a bore 67 which connects the right end of lateral chamber 44 with the outlet chamber 68. This valve is opened when 15 pressure in the upper portion of the pump chamber is greater than pressure in the chamber 68 and is maintained closed by helical spring 69. The chamber 68 is connected to perforated boss 70 on the outside of the pump casting as seen in Fig. 1, this boss being threaded to receive a 20 suitable pipe or conduit leading to the machine to be operated.

The upper cylinder head 21 is of inverted cup-like form with an inner compartment 72 which houses the head of an auxiliary or supplemental inlet valve 73 of identical construction to the inlet and discharge valves of the pump. The upper end of this valve is open to the reservoir but the valve is maintained closed by means of 30 spring 75 abutting against the upper face of perforated washer 76 held in position against the underside of the upper cylinder head by means of the main pump spring 42.

The lower end of this pump spring bears on 35 the top of the piston 28 in an annular area surrounding an upward projection 78. This upward projection houses the upper end of a valve chamber formed by an axial bore 79 in the piston as an extension of the one receiving the screw threaded end 29 of the piston rod. This bore is connected by a small opening 80 through the top of the piston into the upper pump chamber. The bore 79 houses the piston transfer valve 81. This valve comprises a length of rod with longitudinal 40 grooves and intermediate ridges to provide a close sliding fit in the bore. The lower end of the rod is tapered to provide a conical valve structure for cooperation with a seat at the junction of the upper end of the piston rod and a central bore 82 therein. This bore is connected to the surface of the piston rod just beneath the lower face of the piston by means of radial bores 83. The valve 81 is normally closed by means of 45 a spring 84 engaged between the upper end of the same and the underface of the head of the piston.

The normal pumping operation at relatively 50 low pressures may now be described. Assuming the reservoir 11 to be filled with suitable liquid and with the filler cap open, the pedal 35 is depressed, lifting the piston and reducing the pressure in the inlet chamber 45. Atmospheric pressure on the liquid in the reservoir then forces inlet valve 57 open and liquid from the reservoir 55 flows into 45 and into the space at the lower end of the pump cylinder now evacuated by the piston. During the initial or priming operation it is preferred that the supplementary inlet valve 73 be depressed to open position by means of a 60 suitable tool inserted through the filler opening of the reservoir. This permits the escape of air trapped in the pump mechanism and also permits liquid which is normally above the level of the opening of this valve to flow into the pump chamber to assist in filling it on the down stroke. 70

When the piston reaches the top of its stroke the inlet valve 57 closes under the action of its spring and when the foot is removed from the pedal the pump spring 42 forces the piston downwardly. The oil trapped beneath it is thus placed under pressure and rushes in through the lateral openings 83 and central passage 82 through the piston rod, lifts the transfer valve 81, flows past the same and through the opening 80 into the pump barrel displacing more air. These operations are repeated until no air bubbles are seen to rise from the liquid in the reservoir above the supplementary inlet valve 73 which can now be released for normal operation. Further operation of the pump now causes the pump discharge valve 66 to be lifted each time the piston is raised to deliver oil to the high pressure chamber 68 and thence to the connected apparatus for operating the same.

It will be noted that when the piston is lifted the quantity of oil taken in below the same is determined by the displacement of the piston minus the displacement of the piston rod. In other words, it is the quantity of oil which will fill the annular chamber surrounding the piston rod between the bottom face of the piston and the upper face of the cylinder head minus the small clearance at the cylinder head. The amount of liquid ejected by the top of the piston, however, is equal to the total displacement of the piston. Each successive pumping stroke, therefore, is seen not to provide sufficient fluid to fill the chamber above the piston for full discharge at the next stroke. The additional fluid required for the purpose is equivalent to the displacement of the piston rod and is delivered by the auxiliary inlet valve 73. This occurs because as the piston moves downwardly the quantity of oil flowing through transfer valve 81 is not enough to fill the chamber above the piston and a reduction in pressure occurs there since the discharge valve 66 has closed, and therefore the valve 73 is drawn open. By this means a full quantity of oil equal to the total displacement of the piston is delivered with each stroke of the pump.

Since the diameter of the pump piston is substantial it will be seen that a pressure will finally be developed, if there is sufficient resistance in the tool being operated, so that the effort of pumping becomes laborious. Therefore, to provide for higher pressures to be obtained without too much effort on the part of the operator, the pump is arranged to automatically reduce its capacity of discharge with each stroke and thereby permit the achievement of higher pressures. This is done by causing the pump to operate solely on the basis of the displacement of the piston rod at each stroke, and this is the result of returning to the lower side of the piston on each stroke that amount of liquid above the piston which is the difference between the displacement of the piston rod and that of the piston. This can be achieved by means of a discharge-pressure responsive valve connecting the spaces at the under and upper sides of the piston. For convenience, in the present construction, this return valve is incorporated in the transfer or piston contained valve 81 which for the purpose is provided with a longitudinal central chamber 93 connected to the conical tip by a reduced opening 91. At the junction of the chamber and opening 91 a shoulder is provided for the spring 92, which serves to seat the valve ball 93 on a seat in the disc 95 mounted in a counterbore at the upper end of the valve plunger 81. This disc 75

is perforated as at 96 and is held in position by any suitable means such as by spinning over the thin surrounding metal at the end of the valve plunger as shown at 97.

It will be seen that when the piston is being lifted against a pressure, predetermined by the area of the bore 96 and the strength of spring 92, that the valve ball 93 will be lifted from its seat and fluid above the piston will flow back to the underside. The volume of space beneath the piston, however, is not the equivalent of the volume swept by the upper end of the piston, the difference being the volume displaced by the piston rod, so that this quantity of liquid, equivalent to this piston rod displacement cannot be returned but must be discharged through the discharge valve 66 on each stroke of the pump. It will, therefore, be seen that the pump is automatically converted from one of relatively large capacity per stroke at relatively low pressure to one capable of producing a much higher pressure but with less volume delivered per stroke. A convenient ratio is 5 to 1 achieved by having the piston area 5 times that of the piston rod. Then if the return valve spring is properly adjusted the pump can, for instance, be arranged to deliver a certain quantity of liquid per stroke up to about 200 pounds per square inch pressure and to then deliver $\frac{1}{5}$ of this quantity per stroke up to about 1,000 pounds pressure when the discharge resistance increases beyond 200 pounds.

To complete the apparatus and to permit it to be self-contained, a release valve is provided for returning the liquid from the operated mechanism to the reservoir. This valve operates then between the pressure chamber 68 and the reservoir and is shown in Figure 3 in detail. Preferably the chamber 68 is a circular bore with a horizontal axis in the boss 100, which projects toward the right from the pump cylinder bore. The right hand end of this bore 68 is closed by a screw cap 101 centrally perforated as at 102 to accommodate the stem of a valve 103 not substantially different in construction from the main and auxiliary inlet valves and the discharge valve, except that its stem is much longer and its central passage 104 is connected to the surface of the stem near its outer end by lateral passages 105. Furthermore, the lateral passages just beneath the head are disposed at varying distances from the head and are of increasing diameters as clearly seen at 106 and 107. This release valve is held closed not only by the small spring 69 which holds the discharge valve closed but by a larger and much more substantial spring 110 closely fitting the walls of the bore 68 and bearing against a washer 111 centered on the head of the valve 103 by means of the central pin on the head which accommodates the smaller spring.

The stem of valve 103 is adapted to be slid toward open position by means of a sliding plunger 115 passing through a suitable cylindrical tunnel in the vertical wall of the reservoir, where it is reinforced by an internal boss as shown. This plunger comprising a length of rod of suitable diameter for a close working fit in the tunnel and provided with circumferential grooves to accommodate packings 116 to prevent leakage. Manipulation of the plunger 115 is effected by means of a release lever 117 fulcrumed on pin 118 mounted between spaced lugs 119 formed integral with the main casting.

The lower end of the lever is provided with a suitable stop portion 120 and the upper end is

fashioned into a foot engaging portion 121. A short distance above the pivot the lever is equipped with a transverse pin 122 on which is mounted a roller 123 in a position to contact the end of the plunger 115 when the release lever is pressed with the foot.

It will be seen that after the tool or the like has been operated it will be held in position as long as desired by the action of the discharge valve 66 and the release valve 103, both of which are tight. When it is desired to release the tool, pressure is applied to the release lever 117 in the amount desired to open the release valve 103 and permit return of the liquid from the operated mechanism into the reservoir at a rate determined by the amount of opening of the release valve. It will be appreciated that with tools like hydraulically actuated vises it is not always desirable to have the jaws move apart to their maximum under the action of their spring. Movement of perhaps less than $\frac{1}{8}$ of an inch will usually be sufficient to release the work. This can readily be accomplished by the variable flow adjustments of the release valve, which permit the release of desired quantities of liquid, with rapid and sensitive control eliminating the need for a great deal of pumping at each operation of the tool. Furthermore the two ranges of the pump permit of rapid initial adjustment of a vise (for instance) and then the application of high pressure to finally clamp the work.

I claim:

1. In a liquid pump of the type described, in combination, a housing having a pump barrel and inlet and discharge valves associated with opposite ends thereof, a piston reciprocable in said barrel and having a piston rod on the inlet side thereof, and discharge-pressure responsive means adapted to connect the discharge and suction sides of the piston in the space between said valves when the said pressure exceeds a predetermined value, whereby the liquid on the discharge side of the piston in excess of the displacement of the piston rod is returned to the suction side during each pumping stroke.

2. In a liquid pump of the type described, in combination, a housing having a pump barrel and inlet and discharge valves associated with opposite ends thereof, a piston reciprocable in said barrel and having a piston rod on the inlet side thereof, and discharge-pressure responsive means adapted to connect the discharge and suction sides of the piston within the volume defined between said valves when the said pressure exceeds a predetermined value, whereby the liquid on the discharge side of the piston in excess of the displacement of the piston rod is returned to the suction side during each pumping stroke, said discharge-pressure responsive means being mounted in the piston.

3. In a liquid pump of the type described, in combination, a housing having a pump barrel and inlet and discharge valves associated with opposite ends thereof, a piston reciprocable in said barrel and having a piston rod on the inlet side thereof, a transfer valve in said piston for the passage of liquid from the suction to the discharge side of the piston, and discharge-pressure responsive means adapted to connect the discharge and suction sides of the piston when the said pressure exceeds a predetermined value, whereby the liquid on the discharge side of the piston in excess of the displacement of the piston rod is returned to the suction side during each pumping stroke, said discharge-pressure responsive

sive means being mounted in said transfer valve.

4. In a liquid pump of the type described, in combination, a housing having a pump barrel, an inlet valve at one end thereof and a discharge valve at the opposite end thereof, a piston reciprocable in said barrel and having a piston rod on the inlet side thereof, discharge-pressure responsive means adapted to connect the discharge and suction sides of the piston when the said pressure exceeds a predetermined value whereby the liquid on the discharge side of the piston in excess of the displacement of the piston rod is returned to the suction side during each pumping stroke, and a supplemental inlet valve associated with the discharge side of the piston.

5. In a liquid pump of the type described, in combination, a housing having a pump barrel, an inlet valve at one end thereof and a discharge valve at the opposite end thereof, a piston reciprocable in said barrel and having a piston rod on the inlet side thereof, discharge-pressure responsive means adapted to connect the discharge and suction sides of the piston when the said pressure exceeds a predetermined value whereby the liquid on the discharge side of the piston in excess of the displacement of the piston rod is returned to the suction side during each pumping stroke, a supplemental inlet valve associated with the discharge side of the piston, a liquid reservoir associated with said pump and providing a liquid level above the barrel thereof, said barrel being vertical with the discharge end at the top and said supplemental inlet valve being accessibly positioned for manual opening to bleed the system of air during initial filling with liquid.

6. In a liquid pump of the type described, in combination, a housing having a pump barrel, an inlet valve at one end thereof and a discharge valve at the opposite end thereof, a piston reciprocable in said barrel and having a piston rod on the inlet side thereof, discharge-pressure responsive means adapted to connect the discharge and suction sides of the piston when the said pressure exceeds a predetermined value whereby the liquid on the discharge side of the piston in excess of the displacement of the piston rod is returned to the suction side during each pumping stroke, a supplemental inlet valve associated with the discharge side of the piston, a liquid reservoir associated with said pump and providing a liquid level above the barrel thereof, said barrel comprising a vertical bore in said housing, a head closing the upper end of said bore and housing said supplemental inlet valve and a spring between said head and the piston to return the latter after a pumping stroke.

7. In a liquid pump of the type described, in combination, a housing having a reservoir for liquid, a vertical pump barrel immersed in said reservoir and having an inlet valve connected to the lower end and a discharge valve connected to the upper end, a piston reciprocable in said barrel and having a piston rod on the inlet side thereof, a transfer valve in said piston, a discharge-pressure responsive means adapted to connect the discharge and suction sides of the piston when the discharge pressure exceeds a predetermined value whereby the liquid on the discharge side of the piston in excess of the displacement of the piston rod is returned to the suction side during each pumping stroke, a head closing the upper end of said barrel and a supplemental inlet valve extending through said head and having its upper end immersed in the liquid in said reservoir.

8. In a liquid pump of the type described, in combination, a housing having a reservoir for liquid, a vertical pump barrel immersed in said reservoir and having an inlet valve connected to the lower end and a discharge valve connected to the upper end, a high pressure chamber for connection to a device operated by the liquid under pressure, said discharge valve opening into said chamber, a piston reciprocable in said barrel and having a piston rod on the inlet side thereof, a transfer valve in said piston, a discharge-pressure responsive means adapted to connect the discharge and suction sides of the piston when the discharge pressure exceeds a predetermined value whereby the liquid on the discharge side of the piston in excess of the displacement of the piston rod is returned to the suction side during each pumping stroke, a head closing the upper end of said barrel, a supplemental inlet valve extending through said head and having its upper end immersed in the liquid in said reservoir, and a manually operable release valve adapted to connect said high pressure chamber to the reservoir for the return of the liquid from the operated device.

9. In an apparatus of the type described, in combination, a casting providing a reservoir and an immersed pump housing, a vertical bore through the housing and reservoir top, a head in the housing bore separating it from the reservoir, and providing a pump barrel, a piston reciprocable in said barrel and having a piston rod on the suction side thereof, a lower head drilled to pass said rod, a side chamber adjacent each head and connected to the barrel, an inlet valve opening from the reservoir into the lower chamber, a discharge valve opening outwardly from the upper chamber, a transfer valve in said piston and discharge-pressure responsive means adapted to connect the discharge and suction sides of the piston when the said pressure exceeds a predetermined value whereby the liquid on the discharge side of the piston in excess of the displacement of the piston rod is returned to the suction side during each pumping stroke.

10. In an apparatus of the type described, in combination, a casting providing a reservoir and an immersed pump housing, a vertical bore through the housing and reservoir top, a head in the housing bore separating it from the reservoir, and providing a pump barrel, a piston reciprocable in said barrel and having a piston rod on the suction side thereof, a lower head drilled to pass said rod, a side chamber adjacent each head and connected to the barrel, an inlet valve opening from the reservoir into the lower chamber, a discharge valve opening outwardly from the upper chamber on a horizontal axis, a high pressure chamber supplied by the liquid from the discharge valve, a release valve connecting said high pressure chamber to the said reservoir, said release valve movable in a bore coaxial with that for the discharge valve, a transfer valve in said piston and discharge-pressure responsive means adapted to connect the discharge and suction sides of the piston when the said pressure exceeds a predetermined value whereby the liquid on the discharge side of the piston in excess of the displacement of the piston rod is returned to the suction side during each pumping stroke.

11. In an apparatus of the type described, in combination, a casting providing a reservoir and an immersed pump housing, a vertical bore through the housing and reservoir top, a head in

the housing bore separating it from the reservoir, and providing a pump barrel, a piston reciprocable in said barrel and having a piston rod on the suction side thereof, a lower head drilled to pass said rod, a side chamber adjacent each head and connected to the barrel, an inlet valve opening from the reservoir into the lower chamber, a discharge valve opening outwardly from the upper chamber on a horizontal axis, a high pressure chamber supplied by liquid from the discharge valve, a release valve connecting said high pressure chamber to the said reservoir, said release valve movable in a bore coaxial with that for the discharge valve, a transfer valve in said piston and a pump chamber pressure responsive relief valve adapted to connect the upper side chamber to the reservoir.

12. In an apparatus of the type described, in combination, a casting providing a reservoir and a pump housing positioned to be immersed in the liquid in the reservoir, a vertical bore through the housing and reservoir top, a top head in the housing bore separating it from the reservoir, and providing a pump barrel, a piston reciprocable in said barrel and having a piston rod on the suction side thereof, a lower head drilled to pass said rod, a side chamber connected to the barrel adjacent each head, an inlet valve opening from the reservoir into the lower chamber, a discharge valve opening outwardly from the upper chamber, a high pressure chamber supplied by liquid from the discharge valve, a release valve adapted to connect said high pressure chamber to the said reservoir, a transfer valve in said piston, a supplemental inlet valve extending through the top head whereby it is available for manual opening through the filler bore in the reservoir top and a closure cap for said reservoir.

13. In a liquid pump adapted to automatically change its displacement with discharge pressure changes comprising in combination, a pump barrel having an inlet valve at one end and a discharge valve at the opposite end, a piston, a piston rod at the inlet end of the barrel, a transfer valve in the piston adapted to close an aperture therethrough on the discharge stroke and a discharge-pressure responsive valve mounted in the transfer valve.

14. In a liquid pump adapted to automatically change its displacement with discharge pressure changes comprising in combination, a pump barrel having an inlet valve at one end and a discharge valve at the opposite end, a piston, a piston rod at the inlet end of the barrel, a transfer valve in the piston adapted to close an aperture therethrough on the discharge stroke, a discharge-pressure responsive valve mounted in the transfer valve, and a supplemental inlet valve at the discharge valve end of the barrel to supply a volume of liquid per stroke equal to the different displacements of the opposite ends of the piston.

15. In a liquid pump adapted to automatically change its displacement with discharge pressure changes comprising in combination, a pump barrel having an inlet valve at one end and a discharge valve at the opposite end, a piston, a piston rod at the inlet end of the barrel threaded into the piston, a chamber in the piston open to the barrel at the discharge end, a spring pressed valve plunger having a conical end, a passage in the piston rod providing access between the pump barrel at the inlet end and said chamber, said conical end cooperating to close said passage, and

a spring pressed valve in said valve plunger opening in the opposite direction thereto.

16. A liquid pump adapted to deliver against low pressure the full displacement of its piston and against higher pressure the displacement of its piston rod only, comprising in combination, a pump barrel, a piston in said barrel having a large diameter piston rod, a head closing one end of the barrel and passing said rod, an inlet valve delivering to the rod end of the barrel, a head for the opposite end of the barrel, a discharge valve and a supplemental inlet valve for said latter end, a transfer valve adapted to pass liquid from the rod side to the opposite side of the piston on the intake stroke and to close on the discharge stroke, and a valve sensitive to discharge pressure to connect the two sides of the piston when delivery is against excess pressure whereby only the rod displacement is effective for discharging liquid.

17. In a liquid pump, in combination, a barrel, a piston reciprocable in said barrel, a rod for said piston, heads for said barrel, one bored to pass said rod, separate inlet valves for the two ends of the cylinder, a discharge valve for the end of the cylinder free of the rod, and a transfer passage and valve connecting the barrel portions on opposite sides of the piston, said transfer valve opening automatically on the return stroke of

5
10
15

the piston and the passage being continually open at both ends.

18. In a liquid pump, in combination, a barrel, a piston reciprocable in said barrel, a rod for said piston, heads for said barrel, one bored to pass said rod, an inlet valve for the rod end of the cylinder, a discharge valve for the opposite end of the cylinder, a transfer passage in the piston between the two ends of the cylinder, a check valve in said passage opening toward the opposite end of the cylinder and a supplemental inlet valve to supply the deficiency in liquid passing through said passage.
